(57) **CLAIM**

The ornamental design for an air deflector assembly for truck, as shown and described.

DESCRIPTION

1. Air deflector assembly for truck

1.1 : Perspective

1.2 : Top

1.3 : Bottom

1.4 : Front

1.5 : Back

1.6 : Right

1.7 : Enlarged

Disclosed herein is a design for an Air Deflector Assembly for Truck; the front end of the truck shown in Figure 1.1 shown in broken lines does not form part of the design; a left side view is omitted as it is a mirror image of the right side view; Figure 1.7 is an enlarged view of one of the wishbone-shaped elements shown in Figures 1.1 to 1.6.
